UNITED STATES PATENT OFFICE

149,766

DESIGN FOR AN ICE-CREAM DISHER

Louis Myers, Rockford, Ill.

Application August 30, 1946, Serial No. 132,972

Term of patent 14 years

(Cl. D44—29)

To all whom it may concern:

Be it known that I, Louis Myers, a citizen of the United States, residing at Rockford, in the county of Winnebago and State of Illinois, have invented a new, original, and ornamental Design for an Ice Cream Disher, of which the following is a specification, reference being had to the accompanying drawing, forming a part thereof.

In the drawings:

Fig. 1 is a plan of an ice cream disher embodying my new design;

Fig. 2 is a side elevation;

Fig. 3 is a section through the handle on line 3—3 of Fig. 1.

The essential features of my design reside in the portions illustrated in full lines.

I claim:

The ornamental design for an ice cream disher, substantially as shown and described.

LOUIS MYERS.
